(57) **CLAIM**

The ornamental design for a votive candle, as shown and described.

DESCRIPTION

FIG. 1 is a perspective view of a votive candle showing our new design;

FIG. 2 is a top plan view thereof;

FIG. 3 is a side elevational view thereof, the opposite side elevational view being a mirror image;

FIG. 4 is a front elevational view thereof, the opposite rear elevational view being a mirror image; and,

FIG. 5 is a bottom plan view thereof.

The broken line showing a wick of FIGS. 1, 2, 3 and 4 is for illustrative purposes only and forms no part of the claimed design.
